UNITED STATES PATENT OFFICE.

MICHAEL MUTRO, OF CHESTER, PENNSYLVANIA.

AERIAL BOMB.

1,234,790.

Specification of Letters Patent. Patented July 31, 1917.

Application filed November 20, 1916. Serial No. 132,333.

To all whom it may concern:

Be it known that MICHAEL MUTRO, subject of the Emperor of Austria, residing at Chester, in the county of Delaware and State of Pennsylvania, has invented certain new and useful improvements in Aerial Bombs, of which the following is a specification.

This invention relates to self propelled aerial bombs.

The object of the invention is to provide a bomb of this character in which the exact moment of explosion of the charge may be determined, and in which the destructive results from the explosion shall be utilized to their highest extent.

A further object is to eliminate the employment of a rudder or other steering mechanism of the usual type, and in lieu thereof to cause the propeller to perform the functions of a driver, stabilizer and rudder.

With the above and other objects in view, as will appear as the nature of the invention is to be understood, the same consists, generally stated, in an aerial bomb embodying a shell casing adapted to contain, in separate compartments the explosive charge and the shrapnel, certain of the compartments being in communication whereby when the primer or cap is exploded, the ignition and thus explosion of the various explosives will follow in step-by-step order, but practically instantaneously so that shell will be rent from end to end, thereby liberating the shrapnel, and causing them to be scattered in all directions.

Another feature of the invention is the propelling means which consists of an ordinary propeller driven by a suitable motor, the shaft of the propeller being disposed eccentric to the longitudinal axis of the shell whereby the shell will be maintained in a predetermined position, and will be prevented from being turned on its axis due to rotation. The propeller through suitable mechanism is connected with a blade mounted at the point of the projectile or bomb, the turning of the blade being resisted by the air so that it may be drawn toward the rear of the shell by means of a shaft driven

from the propeller motor. By this means, as soon as the bomb is released and the motor starts its action, the whole device will be driven forward at a rapid rate of speed, operating the shaft that connects with the blade, and causing the latter to approach a primer exploding means, it being understood that the latter operation of the blade may be correctly timed previous to the release of the bomb by turning the blade by hand before the firing so as to cause it to assume a position closer to or further from the firing means.

With these general objects in view, the invention consists in further novel details of construction hereinafter fully described and claimed.

In the accompanying drawing forming a part of the specification and in which like characters of reference indicate corresponding parts,

Fig. 1 is a view in vertical longitudinal section through a bomb constructed in accordance with the present invention.

Fig. 2 is a view in end elevation taken from the rear of the bomb disclosing more particularly the propeller driving mechanism.

Fig. 3 is a vertical transverse section taken on the line 3-3 of Fig. 1.

Fig. 4 is a vertical transverse section taken on the line 4-4 of Fig. 1.

Referring to the drawing, 1 designates the shell or casing of the bomb which may be made of heavy sheet metal, and is of general conical contour, the rear end of the shell being closed by a plug or plate 2 that closes access to the interior of the shell and thus prevents any deterioration of the contained explosive charges, or other damage by moisture.

Secured to the plug 2 is a cap 3 in which is arranged the motor for the propeller, the latter being shown in the present instance as an ordinary clock work mechanism although any other character of motor found adapted to the purpose may be substituted therefor.

Arranged centrally and longitudinally of the shell is a tube 4 one end of which is

seated in the plug 2 and the other end threaded into a partition 5 arranged adjacent to the front end of the shell and forming one wall of the powder receptacle, 5 the other walls 6, 7 and 8 being suitably connected to present a powder compartment for the reception of a suitable powder, preferably slow burning. Arranged within the tube 4 is a shaft 8' the rear end of which 10 carries a gear 9 that drives a pinion 10 carried by the propeller shaft 11. The forward end of the shaft carries an exteriorly threaded part 12 that engages the internal threads of the tube or thimble 13, the outer 15 end of which is provided with a head 14 that is rigidly secured to the blade. This sleeve is mounted in bearings 15 carried by a plate 16 the latter being provided with firing pins 17 designed to explode a fulminate carried by caps 18 projecting from the front wall 7 of the powder receptacle. In order to cause the shaft 8, which would naturally be comparatively light, to remain centered relative to the tube 4, there are 20 employed a plurality of guides or bearings 19 in which the shaft freely revolves, these bearings being held in place by bolts 20 depending from the shell.

Surrounding the tube 4 is a tubular casing 21 the ends of which are closed by plates 22 and 23 and form in conjunction with the tube a gun cotton or other high explosive chamber. Surrounding the explosive chamber 24 is a third chamber 25 which is of frusto-conical contour, and the outer wall 26 of which in conjunction with the outer wall of the explosive chamber 24 provides a chamber or holder for the shrapnel. In addition to the wall 5 of the powder chamber 40 which is provided with a series of orifices 27 there is a second partition 28 provided with a series of orifices 29, the two partitions 27 and 28 in conjunction with the longitudinal cylindrical extension 30 providing three gas 45 holding chambers 31, 32 and 33, the latter chamber communicating with the chamber 32 through a series of orifices 34. The gas chambers are supplied with gas through the filling tubes 35 operating in the usual manner.

When the parts have been assembled as shown in Fig. 1, a brake lever 36 which normally engages with one of the blades of the propeller 37 is swung on its pivot, therefore permitting the propeller to drive the bomb on a horizontal plane through the air. As described, the rotation of the propeller shaft drives the shaft 8 and causes the latter through the nut 12 and thimble 13 to shift the blade rearward or toward the propeller, the blade being prevented from turning through the resistance presented by the air. At the proper instant, the firing pins will explode the caps 18 whereupon the

charge of slow burning black powder will be 65 ignited, fire backward into the gas chamber and ignite the contents thereof, and this ignited gas will pass through suitable ports 38 into the chamber 24 containing the gun cotton or other high explosive, whereupon 70 the shell will be disrupted and torn asunder and the shrapnel will be driven in all directions by the explosive. The improvements herein described while simple in character will be found thoroughly efficient for 75 the purpose designed, and may be carried into effect without the necessity of the employment of expensive machinery for the purpose.

It will be understood that the gas used 80 must necessarily be a combustible gas such as a mixture of hydrogen with a little oxygen, the hydrogen serving also to render the projectile light through its low specific gravity. It will also be understood that the primers 85 18 employed must necessarily be of such a type as to be very sensitive to impact or friction since the movement of the points 17 rearwardly will not produce a heavy blow on account of the slow speed at which these 90 points will move. These sensitive primers can of course be suitably arranged through the employment of a proper explosive, it being well known that many nitrogen compounds are so unstable that a very slight 95 pressure will effect their explosion.

It will be noted that by reason of the position of the propeller 37 below the axis of the shell and of the disposition of the motor at the rear and the powder charge at the 100 front the device may be so balanced as to tend at all times to maintain its horizontal position, the offsetting of the propeller shaft 11 also aiding in this by keeping the center of gravity below the axis of the propeller. 105

What I claim is:—

1. An aerial bomb comprising a shell or casing, a blade at the forward end of the casing, a stem projecting rearwardly from the blade and slidably and rotatably mounted in the forward end of the shell, explosives within the shell; means operated by rearward movement of the blade to ignite the explosives, a propeller at the rear end of the shell, positive driving means for the propeller, including a shaft extending in alignment with the stem, and a screw connection between the shaft and stem whereby movement of the propeller driving mechanism 115 will move the blade rearwardly.

2. An aerial bomb comprising a shell or casing, a blade at the forward end of the casing, a hollow stem threaded interiorly and projecting rearwardly from the blade, 125 said stem being slidably and rotatably mounted in the forward end of the casing, said blade effecting resistance to rotation of

said stem during passage of the shell through the air, explosives within the shell, means operated by the rearward movement of the blade to ignite the explosives, a propeller at the rear end of the shell and positive driving means for said propeller including a shaft extending axially of the shell and having a threaded head on its forward end engaging in the threaded stem.

In testimony whereof I affix my signature 10
in the presence of two witnesses.

MICHAEL MUTRO.
